VACUUM CLEANER HOUSING

Richard Lawrence Jakubowski, P.O. Box 1412,
Fort Myers, Fla. 33902

Filed Jan. 28, 1974, Ser. No. 437,539

Term of patent 14 years

Int. Cl. D7—05

U.S. Cl. D7—166

FIG. 1

FIG. 2

FIG. 3

FIG. 4

FIG. 5

FIG. 1 is a front perspective view of a vacuum cleaner housing showing my new design.

FIG. 2 is a top plan view thereof.

FIG. 3 is a side view thereof.

FIG. 4 is a side view of the opposite side thereof.

FIG. 5 is a rear elevational view thereof.

I claim:

The ornamental design for a vacuum cleaner housing, as shown and described.
